UNITED STATES PATENT OFFICE.

FRANK MAUSER, OF NORTH ATTLEBOROUGH, MASSACHUSETTS.

DESIGN FOR THE BACK OF A BRUSH.

SPECIFICATION forming part of Design No. 19,334, dated October 1, 1889.

Application filed August 21, 1889. Serial No. 321,518. Term of patent 3½ years.

To all whom it may concern:

Be it known that I, FRANK MAUSER, of North Attleborough, in the county of Bristol and State of Massachusetts, have invented and produced a new and original Design for Backs of Hair-Brushes, Hand-Mirrors, and Similar Toilet Articles, of which the following is a specification, reference being had to the accompanying mounted photograph, forming part thereof.

The photograph is a rear view or view of the back of a brush or hand-glass showing my design.

Extending up the center of the back from near the point where the handle is joined is a spray or branch A of aigrette ornamentation in relief, flanked by smaller tufts B, of a similar character, and flowers C. A curved or V-shaped fringe D extends over the top of the spray A from one side to the other of the back. Aigrette tufts E are placed in the

upper corners, and sprays F, of a similar nature, are located at the stem of the spray A. The handle is ornamented at H with aigrettes and at I with fringe. The sides of the back are waving, being convex centrally at J and concave between the centers and ends at K, while the end is concave at L. 25

All the ornamentation described is in relief. 30

What I claim is—

The design for a back for hair-brushes, hand-mirrors, and similar toilet articles herein shown and described, the same comprising the aigrette sprays and work or ornamentation A B E F H, flowers C, and fringes D I, all arranged substantially as shown and set forth. 35

FRANK MAUSER.
